CLAIM

The ornamental design for a popcorn maker as shown and described.

DESCRIPTION

FIG. 1 is a top, front and left side isometric view of a popcorn maker showing our new design;

FIG. 2 is a bottom, front and left side isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view, the right side elevation view being a mirror image thereof;

FIG. 8 is a cross-sectional view taken along line 8-8 of FIG. 3; and,

FIG. 9 is a cross-sectional view taken along line 9-9 of FIG. 3.

The broken lines in the drawings depict portions of the popcorn maker that form no part of the claimed design.
